(57) **CLAIM**

The ornamental design for a tray for telescoping ladder, as shown and described.

DESCRIPTION

FIG. 1 is a perspective view of a telescoping ladder with a tray in an expanded use position showing my new design; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom view thereof; FIG. 8 is a perspective view of the telescoping ladder with the tray of FIG. 1 in a collapsed storage position showing my new design;

FIG. 9 is a front elevation view thereof; FIG. 10 is a rear elevation view thereof; FIG. 11 is a left side elevation view thereof; FIG. 12 is a right side elevation view thereof; FIG. 13 is a top plan view thereof; and, FIG. 14 is a bottom view thereof.

The broken lines shown in the figures are for the purpose of illustrating environment and form no part of the claimed design.
